WHEEL

Frank H. Le Jeune, Detroit, Mich., assignor, by
mesne assignments, to The Kelsey-Hayes
Wheel Company, Detroit, Mich., a corporation
of Delaware

Application April 25, 1932, Serial No. 607,479

10 Claims. (Cl. 22—203)

The invention relates to wheels and refers more particularly to hubs of motor vehicle wheels. One of the objects of the invention is to provide an improved construction of hub. Another object 5 is to provide an improved construction of combined hub and drum. A further object is to provide an improved method of manufacture, whereby the hub may be economically made.

These and other objects of the invention will 10 become apparent from the following description, taken in connection with the accompanying drawing, in which:

Figure 1 is a sectional view illustrating a hub embodying my invention and also the method of 15 forming the same;

Figure 2 is a similar view illustrating a modification.

Referring to Figure 1, 1 is the hub of a front motor vehicle wheel which comprises the sheet 20 metal member 2 and the cast metal member 3 within the sheet metal member and formed to receive the usual anti-friction bearings. The sheet metal member has the annular portion 4 and the integral annular radially outwardly extending portion 5 formed at its periphery with the transverse annular portion 6, the portions 4, 5 and 6 forming the shell portion of the hub. The cast metal member 3 is formed by centrifugally casting molten metal, such as iron, within this shell 25 portion at a temperature such that the cast metal member is fused with and molecularly bonded to the portions 4, 5 and 6.

The sheet metal member 2 in the present instance also has the annular radially outwardly 30 extending portion 7 and the transverse annular portion 8 at its periphery, these portions 7 and 8 forming an integral part of the sheet metal member and forming the shell portion of the brake drum 9. The radially extending portion 7 connects into the transverse annular portion 6 and 35 is axially offset rearwardly from the radially extending portion 5 and is preferably provided with the radially extending reinforcing ribs 10. The annular portion 8 is also preferably provided with 40 the encircling hollow ribs 11. 12 is a cast metal member within the annular portion 8 and preferably formed by centrifugally casting molten metal, such as iron, within this latter portion at 45 a temperature such that the cast member 12 is fused with and molecularly bonded to the annular portion throughout its extent.

In the manufacture, a sheet metal and preferably sheet steel blank is fashioned by a suitable stamping or drawing or rolling operation, or by a 50 combination thereof, to form the annular portions

4, 6 and 8 with the intermediate radially extending portions 5 and 7. The combined hub and drum shell is then positioned within and secured to the chuck 13, after which the solid core 14 and the hollow core 15 are inserted into place, the latter being secured to the annular weight 16 preferably formed of iron. The core 14 has a reduced portion extending through the axial opening 17 in the radially inwardly extending annular flange 18 at the front end of the annular portion 4 and 10 the enlarged portion of this core 14 is spaced from the inner surface of the encircling part of the annular portion 4 to provide an annular space for receiving the molten metal which forms the front end portion of the cast metal member 3. 15 The core 15 has the axial and radial openings 19 and 19' therethrough, the latter extending between the supporting portions of the core which engage and rest upon the core 14. The core 15 is so formed that it is spaced from the encircling 20 part of the annular portion 4 and also spaced from the radially outwardly extending portion 5 to form the remainder of the cast metal member 3, including the radially outwardly extending annular flange 20. Both the cores 14 and 15 25 may be formed of dry sand in the usual manner and the core 15 may be provided with the gas vents 21 which lead from the pocket formed in this core to make the rear end portion of the cast metal member 3. The periphery of the radially 30 outwardly extending portion of the core 15 contacts with the terminal portion of the transverse annular flange 6 and the arrangement is such that the two cores 14 and 15 confine the molten metal 35 during the pouring. After the cores have been inserted into place with one resting upon and supported by the other, the chuck is then rotated and molten metal, such as cast iron, may be poured through the pouring spouts 22 and 23 to 40 form the cast metal member 3 and the cast metal member or liner 12, the temperature of this molten metal and also the temperature of the sheet metal member 2 being such that the molten metal fuses with and is molecularly bonded to 45 the sheet metal member.

In the modification shown in Figure 2, the hub is a rear wheel hub which may be more readily formed. The sheet metal member forming the shell portion 24 of this hub also has an integral part forming the brake drum shell portion 25. 50 With this construction but one dry sand core 26 is necessary to retain the molten metal during the centrifugal casting of the cast metal portion 27 of the hub. This core is secured to and held in place by the annular weight 28 preferably 55

formed of iron, which latter engages and is supported by the radially extending portion of the brake drum and more particularly its reinforcing ribs. Both the centrifugally cast portion 5 27 and the centrifugally cast brake engaging portion or liner 29 of the brake drum may be formed at the same time.

What I claim as my invention is:

1. In a wheel, a combined hub and drum, comprising a one-piece sheet metal member having annular portions of different diameter and integrally connecting axially offset radially extending portions, and a member cast within the annular portion of smaller diameter and having a radially extending portion at the side of one of said radially extending portions, said cast member forming with said sheet metal member a wheel hub having a radially extending flange.
2. The method of forming a combined hub and drum of a wheel, which comprises fashioning a sheet metal blank to produce annular portions of different diameter and intermediate axially offset radially extending portions, centrifugally casting molten metal within the annular portion 15 of smaller diameter and at the side of its connecting radially extending portion, and confining the molten metal during the casting.
3. In a wheel, a hub shell having an annular portion which forms a hub and a portion extending outwardly from said annular portion, a member cast within the annular portion and having an outwardly extending portion at one side of the outwardly extending portion aforesaid of the shell and cooperating with the latter portion to 25 form an outwardly extending flange on the annular portion.
4. In a wheel, a hub shell having annular portions of different diameters connected together by a radially extending portion, the annular portion 30 of greater diameter being pressed outwardly at the juncture of the same with the radial portion to form a recess, and a member cast within the annular portion of smaller diameter and having a radially extending portion at one side of the radial portion of the shell projecting into said 35 recess.
5. In a wheel, a hub shell having an annular portion forming a hub and having another annular portion of greater diameter than the annular portion aforesaid and connected to the latter by a radially extending portion, and a centrifugally cast member within the annular portion 40 of smaller diameter having a radially extending portion at one side of the radial portion of the shell and abutting the annular portion of the latter of greater diameter and cooperating with the radial portion of the shell to form a radially outwardly extending flange on the hub.
6. In a wheel, a member having annular portions of different diameters provided with radial-

ly extending portions, a member cast within the annular portion of smaller diameter and having a radially extending portion at one side of the portion extending radially from the latter annular portion forming a wheel hub with a radially extending flange, and a member cast within the annular portion of greater diameter forming with the latter a brake flange.

7. In a wheel, a member having axially offset annular portions of different diameters provided with radially extending portions integrally connected by an axially extending portion, a member cast within the annular portion of smaller diameter and having a radially extending portion at one side of one of the radially extending portions 15 aforesaid in abutting relation to said axially extending portion, said cast member forming a wheel hub having a radially extending flange, and a member cast within the annular portion of greater diameter in abutting relation to the other 20 of the radially extending portions of said member to form a brake flange.

8. The method of forming a wheel hub having an outwardly extending flange which consists in fashioning a sheet metal blank to form a shell 25 with an annular portion which forms a hub and with a portion extending outwardly from said annular portion, centrifugally casting molten metal within the annular portion and at one side of the outwardly extending portion to form with the latter portion the outwardly extending flange aforesaid on the hub.

9. The method of forming a wheel hub having a radially outwardly extending flange which consists in fashioning a sheet metal blank to produce 30 a shell having an annular portion forming a hub and having another portion of greater diameter than the annular portion aforesaid and connected to the latter by an outwardly extending portion, centrifugally casting molten metal within the 40 annular portion of smaller diameter and at one side of the outwardly extending portion in abutting relation to the annular portion of greater diameter to form with said outwardly extending portion the radial flange aforesaid on the hub.

10. The method of forming a combined hub and drum of a wheel, which consists in fashioning a sheet metal blank to produce annular portions of different diameters and intermediate axially offset radially extending portions integrally connected by an axially extending portion, centrifugally casting molten metal within the annular portion of smaller diameter and at one side of its radially extending portion in abutting relation to the axially extending portion, and centrifugally casting molten metal within the annular portion 55 of greater diameter in abutting relation to its radially extending portion.
